JOHN FRANK ROGERS, OF CLEVELAND HEIGHTS, OHIO, ASSIGNOR TO THE WELLMAN-SEAVIER-MORGAN COMPANY, OF CLEVELAND, OHIO, A CORPORATION OF OHIO.

REVERSING-VALVE MECHANISM.

1,379,696.

Specification of Letters Patent. Patented May 31, 1921.

Application filed February 23, 1918. Serial No. 218,688.

To all whom it may concern:

Be it known that I, JOHN FRANK ROGERS, a citizen of the United States, residing at Cleveland Heights, in the county of Cuyahoga and State of Ohio, have invented a certain new and useful Improvement in Reversing-Valve Mechanism, of which the following is a full, clear, and exact description.

10 This invention is an improvement upon the kind of reversing valve mechanisms wherein the valve is hung, on both sides thereof, from the upper ends of arms that are fixed to, preferably, two rock shafts; 15 whereby, as said rock shafts are rocked, the valve will be lifted from one operative position and moved over toward and then lowered to the other operative position.

The Rose Patent No. 1,045,749 shows and 20 describes reversing valve mechanism which is typical of the mechanism to which the instant invention is applicable.

In reversing valve mechanism of the type referred to the valves are large and heavy. 25 To initiate the movement of the valve from one operative position requires the application of great power, sufficient to overcome the dead weight of the valve and the frictional resistance of the associated mechanism; but the power required to continue the movement of the valve becomes progressively less, until, when the valve reaches the center of its path, no more power is required to carry it over the center than enough to 30 overcome the frictional resistance of the moving parts. After the valve has passed the center, however, a rapidly increasing power is required to hold the valve back and prevent it from dropping with destructive force to its seat. To meet these requirements powerful and expensive operating mechanism has heretofore been employed.

The object of this invention is to minimize 45 and substantially equalize the force required to move the valve through the entire path it must travel in moving from one operative position to the other.

This invention involves the employment of 50 a counterbalancing weight of varying resistance and suitable mechanism to cause it to so coöperate with the valve and its usual associated mechanism that the valve will be substantially counterbalanced at all times, 55 with the result that one man can move it,

or, if mechanism is provided for doing this, that mechanism may be simple and inexpensive. The invention is shown in the drawing and hereinafter described and definitely pointed out in the appended claims. 60

In the drawing, Figure 1 is a side elevation of a reversing valve mechanism which embodies my invention; Fig. 2 is a plan view of the same,—and Fig. 3 is a transverse vertical sectional view in the plane of line A—B 65 on Fig. 1.

Referring to the parts by reference characters, 1 represents the trough-shaped base of the valve mechanism,—which base is formed with three ports 4, 5, 6, each surrounded by an upwardly extended flange 7. 70

8 represents the hood whose lower edge rests upon the base submerged in the water which said trough-shaped base contains.

13 represents the valve which is of D- 75 shape, and of such size that it may embrace and connect the ports 5 and 4 while in one operative position, and the ports 5 and 6 when in the other operative position. This valve is commonly made of metal and is 80 lined with fire brick or other heat resisting material. Two parallel rock shafts 15 and 16 extend transversely across the base below the valve and the hood. Arms 17 are fixed to both rock shafts on opposite sides 85 of the hood and outside of the same. The two arms 17 on each side of the hood and valve are connected by a link 21 so that the rock shafts must rock in unison.

J-shaped bars 19 are respectively hung 90 from the upper end of the several arms 17,—preferably upon the same pivots 18 which connect said arms with the links; and these bars 19 go under the lower side edges of the hood and engage the lower side edges of the 95 valve. When, therefore, the rock shafts are rocked the valve will be lifted from one operative position as shown by dotted lines in Fig. 1, and moved over toward and lowered to the other operative position, as shown 100 also by dotted lines in Fig. 1. In this same figure this valve is shown in full lines in the center of its path of travel.

The mechanism to the extent above described is known and constitutes the valve 105 mechanism to which the present invention is applicable.

Pivoted to a suitable support at one side of the hood is a segment 20. A chain 21^a is fixed to this segment adjacent one edge 110

thereof and extends therefrom in a groove in the periphery thereof to the opposite edge thereof, and thence between two sheaves 22, 23, mounted side by side at the 5 side of the hood. This chain is connected with the link 21 on the same side of the hood and near the middle of said link. A pendulous weight 25 of varying resistance is connected with this segment, and in position 10 such that when the valve is in its middle position, as shown by full lines in Fig. 1, this arm extends vertically downward in a radial direction with respect to the axis of the segment; and this arm carries on its 15 lower end a weight of sufficient size to effect the desired counterweighting of the valve.

When the valve moves from its middle position in either direction, that is, toward either valve seat, this weight will be swung 20 upward from its vertical position, and will, with increasing force, counterbalance the valve in proportion to the need for such counterbalancing. The arm of this weight will be near the horizontal position when 25 the valve is in either operative position, and the lever arm should be of such length and the weight of such ponderosity that when in this position it will substantially counterbalance the valve when the latter is seated, 30 so that a slight force applied to the mechanism will move it and cause the valve to lift. As the valve moves from its seat toward its center position the power required to move it gradually decreases, and the 35 counterbalancing effect of the weight proportionately decreases, until when the valve is in the middle of its path the weight is hanging vertically downward. When the valve proceeds beyond the middle of its 40 path toward either seat, the weight is gradually swung upward and exercises an increasing resisting power upon the valve which is substantially proportionate to the requirements of the case, so that therefore 45 the weight will be substantially counterbalancing the valve at all times, and a minimum of power will be required to produce the required valve. The small power to move the valve may be applied to an operating lever 30 that may be fixed to one of 50 the rock shafts 15, 16.

As a refinement of the described apparatus, and as aiding somewhat to the efficiency of the described mechanism, the periphery 55 of the segment is not the arc of a circle. The radial distance from the axis of the segment to the part of the periphery with which the chain is tangential when the weight is hanging vertically downward, (as 60 when the valve is in the middle of its act) is longest; and from this point around through the point with which the chain is tangential when the weight is at its highest point, the radius gradually decreases so as 65 to cause the weight to exercise an increasing

leverage through the described mechanism on the valve.

Having described my invention, I claim:—

1. The combination of a reversing valve which is movable back and forth through 70 a definite path from one operative position to another, arms which are pivoted at their lower ends and which extend upwardly on opposite sides of the valve, valve supporting means connecting said valve with the 75 upper ends of said arms, a pivoted segment, a chain connected therewith and extending over the periphery of said segment, a sheave over which said chain passes and extends downward, means operatively connecting 80 the depending end of said chain with the described valve mechanism, a radial arm, a weight fixed thereto, said arm being connected with said segment in such position substantially as described that when the 85 valve is substantially at the middle of its path of travel said weighted arm will hang vertically downward:

2. The combination of a reversing valve which is movable back and forth through 90 a definite path from one operative position to another, two transversely extended rock shafts which pass beneath said valve, two arms connected with each rock shaft and extending upwardly opposite sides of the 95 valve, a link on each side of the valve connecting the two arms on that side, and valve supporting means connecting said valve with the upper ends of said arms, a pivoted segment, a chain connected therewith and extending over the periphery of said segment, a sheave over which said chain passes and extends downwardly, means operatively connecting 100 the depending end of said chain with the described valve mechanism, a radial arm, a weight fixed thereto, said arm being connected with said segment in such position substantially as described that when the 105 valve is substantially at the middle of its path of travel said weighted arm will 110 hang vertically downward.

3. The combination of a reversing valve which is movable back and forth through 115 a definite path from one operative position to another, two transversely extended rock shafts which pass beneath said valve, two arms connected with each rock shaft and extending upwardly on opposite sides of the valve, a link on each side of the valve connecting together the two arms on that 120 side, and valve supporting means connecting said valve with the upper ends of said arms, a cam shaped segment, a chain connected therewith, and extending in contact with the periphery thereof, a sheave over 125 which said chain after leaving the segment passes and extends downwardly, which chain is connected with a part of the described valve mechanism, a weighted arm fixed to said segment in such relative position that 130

it will extend in a radial direction vertically downward when the valve is in the middle of its path of travel,—said segment having the longest effective radius at a point 5 with which the chain is tangential when the weight is hanging vertically downward and being of decreasing radius therefrom toward

that end of said segment toward which the tangential point travels as the weight is being raised.

10

In testimony whereof I hereunto affix my signature.

JOHN FRANK ROGERS.
